UNITED STATES PATENT OFFICE.

EDWARD JHON LIDDICOAT AND ALBERT W. UTZINGER, OF ASTORIA,
OREGON.

BEER-COOLER.

SPECIFICATION forming part of Letters Patent No. 366,011, dated July 5, 1887.

Application filed August 7, 1886. Serial No. 210,301. (No model.)

To all whom it may concern:

Be it known that we, EDWARD JHON LIDDICOAT and ALBERT W. UTZINGER, both of Astoria, in the county of Clatsop and State of Oregon, have invented a new and Improved Beer-Cooler, of which the following is a full, clear, and exact description.

Our invention relates to an apparatus for cooling beer or other beverage kept on draft; and the invention has for its object to provide a simple, inexpensive, and durable cooler of this class, which may be quickly attached to and removed from the kegs holding the beverage, and will operate effectively to cool the beverage with a comparatively small quantity of ice.

The invention consists in certain novel features of construction and combinations of parts of the cooler and its combination with the beer-keg and its tap, all as hereinafter fully described and claimed.

Reference is to be had to the accompanying drawings, forming a part of this specification, in which similar letters of reference indicate corresponding parts in all the figures.

Figure 1 is a side elevation of the improved beer-cooler attached to a beer-keg as when in use. Fig. 2 is a vertical sectional elevation of the cooler and keg. Fig. 3 is a front view thereof; and Fig. 4 is a sectional plan view of the cooler.

The beer-cooler is made with a box, A, having a back wall, a, a front wall, a', two side walls, a² a², and a bottom, a³, the walls a' a² a³ being made with double air-spaces, as at a' a⁴, which preferably are lined with paper or other approved material being a non-conductor of heat. The two inner vertical partitions of the front and side walls are lower than their outer sheathing to give room at the top of the box A for a removable cover, B, the space below which forms a chamber, D, in which the beer-cooling coil and ice are placed, as presently explained. Above the cover B there is provided an air-space, b, above which an outer removable cover, E, is placed.

To the back of the cooler-box A there is fixed a round block, F, of proper size to fit within the front chine, g, of a beer-keg, G, as shown in Fig. 2 of the drawings. The back wall, a, of the box A and also the block F are

slotted vertically at their centers for a considerable distance from their tops, as at a⁵ f, respectively, to allow passage of a tap, H, fixed in the head of the beer-keg, into these slots as the cooler is raised to enter the block F within the chine of the keg, and when this is done hooks i on the ends of two metal straps or rods, I I, will be engaged with the rear chine, g', of the keg, and when thumb-nuts J J on the outer ends of the rods I I are tightened outside the front of the cooler the hook-rods I i will hold the cooler securely to the front end of the keg. The clamp-rods I pass through the upper air-space, b, of the cooler, as shown most clearly in Fig. 2. After the cooler is attached to the keg, as above described, a slide, K, which is fitted to the vertical slot a⁵ of the back wall of the box A, will be inserted or slid into said slot, as shown in Figs. 2 and 3, and will rest on the tap H. A packing, L, of rubber or other suitable material, is fixed to the cooler and interposed between the front end or chine of the keg G and the back wall of the cooler to insure a tight joint of the cooler to the keg and prevent passage of air to the interior of the cooler.

In the bottom of the ice-chamber D of the cooler there is placed a coil, M, of pipe, one end of which will be connected by a union-coupling with the tap H, and its other end is connected with a tap, N, outside of the cooler-box, and from which the beer will be drawn as required.

Ice O will be filled into the chamber D around and over the cooling-coil M, and when the covers B E are applied at the top of the cooler all is ready for use. A tap or faucet, P, allows drainage of water from the ice-chamber.

It is obvious that the beer will be cooled as it stands in or passes through the ice-covered coil M on its way to the cooler-tap N; hence the beer may always be delivered to the consumer at an agreeable temperature.

To remove the cooler from an empty keg and attach it to a full keg requires but a few minutes' time, as it is only necessary to remove the covers E B and the slide K and disconnect the tap H from the coil M and loosen the thumb-nuts J of the clamp-rods I and detach the rod-hooks i from the keg, whereupon the cooler may be drawn outward to cause its

block F to clear the chine *g* of the keg, and the cooler may then be lowered from the tap of the empty keg and adjusted to the tap and chine of the full keg and fastened thereto, as 5 above described.

We find in practice that this cooler, aside from the advantages resulting from the simple method of attaching it to the kegs, effects a large saving in the quantity of ice required to 10 cool the beer over other methods of refrigeration.

Having thus described our invention, what we claim as new, and desire to secure by Letters Patent, is—

15 1. The combination, in a beer-cooler, of a refrigerating-box, as at A, slotted at *a*⁵, and provided with a block, F, slotted at *f*, a slide or cover, K, fitted to the slot *a*⁵, and hook straps or rods *I i*, having nuts *J* or equivalent tighteners, all adapted for operation substantially 20 as herein set forth.

2. The combination, with the refrigerating-

box A, having a slot at the back to receive the tap of a beer-keg and a slide or cover fitted to said slot, of a packing, L, for interposition 25 between the cooler-box and the keg, substantially as shown and described.

3. In a beer-cooler, the refrigerating-box A, slotted at *a*⁵, and provided with a block, F, slotted at *f*, and a slide or cover, K, a pipe-coil, M, placed in the ice-chamber of the box A and provided with a tap, N, and hook straps or rods *I i*, having nuts *J* or equivalent tighteners, in combination with a beer-keg, G, having a tap, H, connected to one end of the coil 30 M and entering the slots *a*⁵ *f* of the cooler, substantially as and for the purposes herein set forth.

EDWARD JHON LIDDICOAT.
ALBERT W. UTZINGER.
